United States Patent Office

Des. 192,095
Patented Jan. 16, 1962

192,095

CAN OPENER

Arthur R. Colley, Box 21, Vincent, Ala.

Filed Nov. 21, 1960, Ser. No. 62,903

Term of patent 14 years

(Cl. D44—29)

FIG. 1

FIG. 2

FIG. 3

FIG. 1 is a top plan view of the can opener showing my new design;

FIG. 2 is a side elevational view thereof; and

FIG. 3 is a bottom plan view thereof.

I claim:

The ornamental design for a can opener, as shown.
